United States Patent Office

Des. 190,798
Patented July 4, 1961

190,798

BUILDING

Elmer Harland Daniels, Ann Arbor, Mich., assignor to Schoolmaker, Incorporated, Ann Arbor, Mich., a corporation of Michigan

Filed June 7, 1956, Ser. No. 41,806

Term of patent 14 years

(Cl. D13—1)

FIG. 1 is a front perspective view of a building showing my new design,

FIG. 2 is a rear perspective view thereof,

FIG. 3 is a front elevation of the building,

FIG. 4 is a rear elevation thereof, and

FIGS. 5 and 6 are end views taken from the right and left, respectively, of FIG. 1.

I claim:

The ornamental design for a building, as shown.
